United States Patent Office

Des. 202,984
Patented Nov. 23, 1965

202,984

FOOT REST

Alfred House, Preston, Ontario, Canada, assignor of one-half to Clarence H. Bieman, Clifford, Ontario, Canada

Filed Dec. 14, 1964, Ser. No. 83,016

Term of patent 14 years

(Cl. D15—8)

FIG. 1 is a perspective view of the foot rest showing my new design;

FIG. 2 is a top plan view thereof; and

FIG. 3 is a side elevational view of the foot rest.

I claim:

The ornamental design for a foot rest, as shown.
